UNITED STATES PATENT OFFICE.

WILLIAM SIEBENMORGEN, OF WESTFIELD, NEW JERSEY, ASSIGNOR TO CORLISS CARBON COMPANY, A CORPORATION OF PENNSYLVANIA.

DEVICE FOR ATTACHING CONDUCTORS TO BRUSHES.

Application filed November 4, 1919. Serial No. 335,597.

To all whom it may concern:

Be it known that I, WILLIAM SIEBENMORGEN, citizen of the United States, and resident of Westfield, in the county of Union and 5 State of New Jersey, have invented certain new and useful Improvements in Devices for Attaching Conductors to Brushes, of which the following is a specification.

My invention relates to devices for attaching conductors to brushes for dynamo-electric apparatus.

The object of the invention is to provide a device of this character, which affords a large area of contact and a high contact 15 pressure between the brush and the attaching member, which is universally applicable to brushes of all sizes and particularly adaptable to brushes carrying large currents, and which is of simple, inexpensive 20 construction.

This object of the invention and certain other features thereof set forth below, are attained as described in the following specification having reference to the accompanying 25 drawings, in which,

Figs. 1 and 2 are front and side elevations, respectively, of the preferred form of device embodying my invention, Fig. 1 being partly in section, the plane of the section being indicated in Fig. 2 by corresponding Roman numerals; Figs. 3 and 4, 5 and 6, views similar to Figs. 1 and 2 but showing modified forms of construction; Figs. 7, an isometric view of a third modified form, and 35 Fig. 8, a view showing a longitudinal section of Fig. 7.

Similar characters of reference denote similar parts in each of the several views.

In Figs. 1 and 2 of the drawing reference 40 character 1 designates a carbon brush having secured thereto conductors or pigtailed designated 2 and 2^a respectively, the brush being for this purpose provided adjacent its upper end with a pair of holes 7, extending 45 between recessed portions 11 and 11^a. The conductors consist of stranded copper wires to the ends of which are secured flattened copper terminal sleeves 3 and 3^a respectively, provided with holes 5 and 5^a for fastening 50 the same to corresponding terminals on the dynamo-electric machine. Midway between their ends the conductors have their strands spread apart and inserted between folded plates, designated 4 and 4^a respectively,

each plate being for this purpose provided 55 with a pair of slots designated 6, in the line of the fold. For the purpose of securing the plates to the brush, they are provided with openings for receiving the shanks of screws designated 8, two of which are provided for each plate. The outer member of each folded plate is dished to accommodate the head of the screw and the inner member of each plate is dished similarly, but to a somewhat smaller diameter, as shown. The 65 screws extend into internally threaded sleeves 8 located in holes 7, and serve there to bind the plates into intimate engagement with the sides of the brush. The dished portions of the folded plates extend, it will 70 be observed, into the holes 7 and serve to prevent lateral sliding movement between the plates and the brush.

In the modification shown in Figs. 3 and 4 the brush is provided with a lateral hole 75 in which a plug of conducting material, 15, is firmly embedded. This plug has four threaded transverse holes which register with holes of like diameter in the brush material, two of these holes being provided 80 in each face of the brush, the holes in one face being staggered with respect to the holes in the other. The folded plates 4 and 4^a are provided with holes which are so spaced that they register with 85 the holes in the brush and the plug. Screws 14 extend through the holes in plate 4 and enter the plug 15 from one side and screws 14^a pass through the holes in plate 4^a to enter the plug from the other side, thus 90 binding the plates securely and firmly against the sides of the brush. The dished portions of the plates 4 and 4^a register with similarly shaped depressions 25 in the sides 95 of the brush, to prevent lateral sliding movement between the plates and the brush.

The modification shown in Figs. 5 and 6 is similar to the one described above, except that in place of the plug 15 the brush is provided with a rectangular bar 20 embedded in a groove extending transversely across the upper face of the brush. The screws 14 and 14^a extend into threaded holes in the bar, and bind the plates 4 and 4^a against the sides of the brush, similarly as 100 in Figs. 3 and 4.

Still another modification of the invention is shown in Figs. 7 and 8 in which two addi-

tional folded plates 4^c and 4^d are attached to the brush, these plates being secured to the end faces of the brush, by means of screws 14^c and 14^d which extend into threaded longitudinal holes in the end of a plug 15^a. The other plates, 4 and 4^a, are secured to the sides of the brush similarly as in Fig. 3.

It will have been observed that in each form of embodiment of the invention there is ample contact area and firm contact pressure between the brush material and the conducting plates so that there is little or no heating even when the brushes are used for high amperage machines. For exceptionally large currents the construction shown in Figs. 7 and 8 is particularly serviceable, although for ordinary purposes the first three forms will be found to give highly efficient results. Ample current carrying capacity between the folded plates, 4 and 4^a, and the terminals of the electric machine is secured by the use of a double conductor with each plate.

Although only a few forms of devices embodying the invention are shown and described herein, it is readily understood that various changes and modifications may be made therein within the scope of the following claims without departing from the spirit and scope of the invention.

What I claim is:

1. In combination, a brush, a plurality of pigtailed therefor, means for securing said pig-tails on opposite faces of the brush, said means comprising a plurality of fastening members extending into the brush from opposite sides thereof and a member interior to the brush for co-operating with both of said fastening members.
2. In combination, a brush, a pair of pig-tails therefor, and means for securing said pig-tails to opposite faces of a brush, said means comprising a pair of plates of conducting material in engagement with said pig-tails, a pair of fastening members extending through each plate into the interior of the brush, and means interior to the brush for receiving the said fastening members and co-operating therewith to secure said plates on said brush.
3. In combination, a brush, a plurality of pig-tails therefor, and means for securing said pig-tails to opposite sides of the brush, said means comprising a member imbedded in said brush and parallel to the said sides thereof.
4. In combination, a brush having a recess on each of two opposite sides, a plurality of conductors, terminals for said conductors embracing the ends thereof, and means for securing the said conductors in the said opposite recesses, said means comprising a member inserted in said brush parallel to the said opposite sides thereof and securing

devices co-operating with said member and 65 said conductors.

5. In combination, a brush, a plurality of folded plates having a slot at each end of the fold, a conductor extending outwardly from each slot, said plates and brush having 70 corresponding transverse openings, a member embedded in the brush, and screws co-operating with said member, one screw extending through each plate to bind the same against the side of the brush. 75

6. In combination, a brush, having an opening, a conductor, a member associated therewith having a projecting portion extending into said opening, and means for securing said member to said brush, said 80 means comprising a plug imbedded in said brush.

7. In combination, a brush, having a plurality of holes, conductors therefor, members associated with said conductors having 85 projecting portions extending into said holes and means associated with said holes for binding said members against the sides of the brush.

8. In combination, a brush, a plug embedded therein having transverse and longitudinal holes, a plurality of conductors, a plurality of members co-acting with the transverse holes in said plug to clamp said conductors to opposite sides of the brush, 95 and a plurality of other members co-acting with the longitudinal holes in the plug to clamp certain other of said conductors to the remaining opposite sides of the brush. 90

9. In combination, a brush, a plug imbedded therein having transverse holes, a plurality of conductors and a plurality of members co-acting with the said transverse holes in said plug to clamp said conductors to opposite sides of the brush. 100 105

10. In combination, a brush, a plurality of recesses therein on opposite sides of the brush, a plurality of pig-tails for said brush, a plug imbedded in said brush and members co-operating with said plug and 110 extending thereinto from opposite sides for securing said pig-tails in said recesses.

11. In combination, a brush, a plurality of pairs of pig-tails therefor, a plurality of plates of conducting material for securing 115 said pairs of pig-tails at opposite faces of the brush, threaded fastening members extending through said plates and into the interior of the brush, and securing means interior to said brush provided with threads 120 for co-operating with the opposed fastening members for securing said plates on said opposite faces.

Signed at New York in the county of New York and State of New York this 3rd 125 day of November A. D. 1919.

WILLIAM SIEBENMORGEN.
